UNITED STATES PATENT OFFICE.

EDWIN D. BEVITT, OF CINCINNATI, OHIO.

SHEET-METAL ROOFING.

SPECIFICATION forming part of Letters Patent No. 518,089, dated April 10, 1894.

Application filed June 8, 1893. Serial No. 476,978. (No model.)

To all whom it may concern:

Be it known that I, EDWIN D. BEVITT, a citizen of the United States, residing at Cincinnati, in the county of Hamilton and State 5 of Ohio, have invented a new and useful Improvement in Sheet-Metal Roofing, of which the following is a specification.

My invention relates more especially to an improvement in the roofing for which United 10 States Letters-Patent No. 422,178 were granted to me February 25, 1890. Part of this invention formed part of the original application for said Letters-Patent, and was divided therefrom.

15 The novel features of construction and their mode of application will be fully hereinafter described and particularly pointed out in the claims.

In the accompanying drawings,—Figure 1 20 is a broken perspective view of a cleat-cap embodying my invention; Fig. 2, an end view of a plain-flanged sheet, to which form of roofing my cleat-cap is peculiarly adapted; Fig. 3, a broken, transverse section showing 25 the manner in which several adjacent plain-flanged roofing-sheets are united together and secured in place on the sheathing by means of my cleat-cap, the seam thereby formed being left open in this view preparatory to the 30 final closing-pass of the usual crimping-tool; Fig. 4, an end elevation of my cleat-cap; Fig. 5, a broken, inverted perspective of Fig. 1; Fig. 6, a longitudinal, sectional elevation of 35 my cleat-cap, taken on line x, x , of the inverted-view Fig. 5; Fig. 7, a bottom-plan view of a single width or narrow strip of flat or plane sheet-metal used in constructing my cleat-cap, slits being shown cut along one edge thereof whereby the fastening-cleats are 40 formed, and constituting the first step in making my cleat-cap; Figs. 8, 9, 10, and 11, views similar to Fig. 7, showing the several steps through which said flat narrow strip or single width of metal passes in making it into 45 inverted-V shape in cross-section and properly bending and disposing the series of laterally-projecting cleats thereon, the last-named view, (Fig. 11,) being a bottom-plan of my invention in its completed state ready for use; Fig. 12, a bottom-plan view similar to Fig. 7, 50 but of a wider strip of plane sheet-metal which I utilize in forming two of my cleat-caps; Fig.

13, a bottom-plan view, showing the strip seen in Fig. 12 with my preferred arrangement of slits cut therein, intermediate its longitudinal edges; Fig. 14, a plan view showing two strips resulting from the slitting-operation seen in the preceding view; and Fig. 15, a plan view similar to Fig. 14, but showing the small slit- 55 ed-ports turned at right angles to the several main-strips, in their first lateral step in the formation of the fastening-cleats.

The longitudinal dotted lines seen in Figs. 8, 9, 13, 14, and 15, respectively indicate the lines on which the metal is bent and folded. 60

A represents an ordinary sheet of roofing, preferably having plain, upturned, longitudinal edges or flanges a , this form being the one to which my invention herein is peculiarly well adapted.

B represents an inverted-V shape strip of metal or cap, fitting over contiguous flanges a of parallel adjoining sheets, and forming a closing-joint or seam therefor.

b represents each one of a series of trans- 70 verse or lateral cleats formed along said cap B, and whereby it is secured in place on the sheathing. These cleats b are preferably constructed integral with the cap, those shown in the drawings being formed on one limb 75 thereof, similar to those shown and described in connection with the inverted-V-flange in said former Letters-Patent. In Figs. 7, 8, 9, 10, and 11, I show how the cleats are formed along one edge of a single width or narrow 80 strip of plane or flat sheet-metal; and in Figs. 12, 13, 14, and 15 I show how the cleats are formed along a wider strip or sheet of similar material, and out of which two caps with 85 cleats are constructed on a somewhat more 90 speedy and economical plan.

In one process, (the first above-named, seen in Figs. 7, 8, 9, 10, and 11,) of forming my cleat-cap, I take a narrow width C of plane sheet-metal, and provide or cut longitudinal 95 end-slits c, c , and intermediate right-angled slits c', c' , along one edge thereof, as most clearly shown in Fig. 7, and similar to the slitting seen in said former Letters-Patent. The narrow strips of metal thus partially severed from the main-piece, are then lapped over at d so that the respective folds thus formed lie at forty-five degree angles to the 100 edge of the said main-piece, and said strips

project laterally at right angles to said edge, as shown in Fig. 8. The said narrow strips and the same width of unslitted metal d' on the edge of said main-piece are then folded 5 over onto the bottom of said piece, as shown in Fig. 9, the line of fold being indicated by dotted lines 1, in Fig. 8, and forming the webs which connect the cleats to the main cap-piece. The main-piece with its cleats and 10 folds are then placed in the die to give the inverted-V shape, in cross-section, (best seen in Fig. 1,) and the cap is now complete ready for use.

In the other process, (the second above-15 named, seen in Figs. 12, 13, 14, and 15,) of forming my cleat-cap, and which is the preferred form, (on account of both speed and economy as hereinbefore stated,) I take a piece D of metal whose width is double that 20 of the piece seen in Fig. 7, less the width of metal used in making the cleats in said first-named process; a double row of longitudinal end-slits e , e' , and right-angled slits f , respectively, are then made down the center of 25 said piece D, the space or width of metal between said double-row of slits corresponding to that necessary in forming the cleats b . This slitting-operation results in the parting or division of the piece D into the two slitted 30 pieces or lengths D' , D^2 , seen in Fig. 14, the slitted portions or strips so provided being then lapped over and disposed sidewise to form the lateral cleats, and the whole subjected to the die or other suitable tool for converting 35 into inverted-V shape in cross-section, as hereinbefore stated in connection with the first-named process. The dotted lines 2 in Figs. 8, 9, 13, 14 and 15, indicate the centers or lines on which the pieces C, D' , and D^2 are bent, 40 and constitute the apexes of said inverted-V caps when complete. The narrow unslitted portions g of the metal in pieces D' and D^2 correspond to those d' , above mentioned, and, while they are somewhat shorter, they fully 45 answer the purpose of connecting the cleats to the said pieces D' and D^2 . In thus cutting and slitting the piece or sheet D and forming two cleat-cap divisions D' and D^2 therefrom, which is less in width than two of said single- 50 width pieces C, as stated, the saving in time, labor, and metal is quite material, and while one less cleat results in the same length of piece for each cap, still I secure six cleats in the two pieces D' and D^2 combined, while 55 there is but four in practically the same width and length of metal, secured in the piece C. In Fig. 15, it will be clearly seen that the opposite ends of both pieces are free from cleats or double thicknesses of metal owing to the 60 provision of said end-slits e , e' , as above set

forth, thus readily adapting the said ends to be suitably bent or folded, or otherwise manipulated, as desired.

In placing the plain-flanged sheets (seen in Fig. 2), together to form a roof, my cleat-caps 65 are applied to each joint or contiguous pair of upturned-flanges a , a , as best seen in Fig. 3, wherein the flange of one sheet stands upright under one limb or side E of the cap, and the adjoining flange of the next sheet 70 stands upright under the other limb or cleated-side F of the cap, the flanged-side of the last-named sheet resting on the cleats of the cap, which cleats have been previously nailed or otherwise secured in place on the sheathing. 75

It will be seen that in the use of my cleat-cap and the ordinary flanged roofing-sheets, herein described and shown, a roof can be very readily, substantially and economically 80 made and repairs thereto greatly facilitated over any form heretofore in use.

I claim—

1. As a new article of manufacture, an anchor-cap for standing-seam roofing, composed substantially of a narrow sheet or plate formed 85 into an inverted-V shape in cross-section, an inner integral fold or strip turned along one edge or side of said sheet, longitudinal end-slits c , c' , and intermediate right-angled slits c' , c' , constructed along the line or web of 90 said fold, and narrow strips of metal, thus partially severed from said cap or main-piece, lapped under at d and bent and disposed laterally across the bottom of the cap, to form anchoring-cleats b , as herein shown 95 and described.

2. In the construction of a joint-cap for sheet-metal roofing, the process herein-described of taking a strip or piece D of less width than that of the combined width of the 100 metal requisite in two single caps, making a longitudinal, double-row of end-slits e and e' , and right-angled slits f , down the center thereof, the space or width of metal between said double-row of slits corresponding to the width 105 of metal necessary in forming the cleats along both resultant divisions D' and D^2 of said piece D, the narrow strips provided by said slits then bent and disposed into lateral cleats and connecting webs, and the divisions D' and D^2 and parts of said cleat-strips being then 110 pressed or otherwise formed into inverted-V or other suitable shape in cross-section, substantially as herein set forth.

In testimony of which invention I have 115 hereunto set my hand.

EDWIN D. BEVITT.
